JOSIAH LETCHWORTH, OF BUFFALO, NEW YORK, ASSIGNOR TO
PRATT AND LETCHWORTH, OF SAME PLACE.

Letters Patent No. 87,686, dated March 9, 1869.

IMPROVED HAMES-RING.

The Schedule referred to in these Letters Patent and making part of the same.

To all whom it may concern:

Be it known that I, JOSIAH LETCHWORTH, of the city of Buffalo, in the county of Erie, and State of New York, have invented a certain new and improved Hames-Ring or Loop; and I do hereby declare that the following is a full and exact description thereof, reference being had to the accompanying drawings, making part of this specification.

The object of my invention is the construction of a hames-ring that is equally adapted to engage with a snap-hook, or to receive the holdback-strap itself, the former being retained in place, and prevented from sliding along the ring, as is the case with the ordinary form of construction, while the bearing for the latter is such as to prevent that unequal wear and strain to which it is subjected when engaging with the rings in common use.

The invention consists of the article itself as a new manufacture, which is constructed with a straight cross-bar, to receive and form the bearing for the strap, when that is used, while the ring or loop-portion, designed to engage the snap-hook, is contracted in size, so as to prevent the play of the latter therein, the ring possessing increased strength, as the result of its peculiar construction.

In the drawings above referred to—

Figure I represents a view of my improved ring attached to a portion of a hames.

Figure II is a view of the ring detached.

Like letters of reference designate like parts in both of the figures.

A is my improved ring.

b, the cross-bar, and

c, the loop for the snap-hook.

The cross-bar is required to be of a length equal to the width of the holdback-strap, for which it forms a bearing, when the strap is used alone, or without a snap-hook.

When a single snap-hook is used, the holdback-strap can be attached to the ring in one of the hames, by passing it through the ring, and around the cross-bar, to which it may remain permanently connected, while the snap-hook, at the other end of the holdback, can be engaged with the loop c, of the ring, in the opposite hames.

It is obvious that a hames-ring should be adapted for use with a holdback-strap alone, and also when provided with snap-hooks.

The construction of the bearings for each is required to be different.

The bearing for the strap should be straight, in order to prevent the unequal wear and strain which result from the use of a curved bearing, as in the case where a simple circular ring is employed.

To obviate this difficulty, rings, with a portion or one side made straight, have been employed.

These, while adapted to be used with straps, are not appropriate for a snap-hook, which would rest in one of the angles at the end of this straight side, thereby causing an unequal strain on the ring, while the connection would present an incongruous appearance.

My improved ring furnishes a suitable bearing for both strap and snap-hook, possesses increased strength from the bracing, which the loop c, in the one case, and the cross-bar in the other affords.

What I claim as my invention, and desire to secure by Letters Patent, is—

The hames-ring, or loop A, constructed with a cross-bar, b, and loop c, as an article of manufacture, substantially as set forth.

JOSIAH LETCHWORTH.
